ATTORNEY

UNITED STATES PATENT OFFICE.

BENJAMIN S. WHITEHEAD, OF NEWARK, NEW JERSEY.

DESIGN FOR A BADGE.

SPECIFICATION forming part of Design No. 23,859, dated December 11, 1894.

Application filed June 7, 1894. Serial No. 513,832. Term of patent 7 years.

To all whom it may concern:

Be it known that I, BENJAMIN S. WHITEHEAD, a citizen of the United States, residing at Newark, in the county of Essex and State of New Jersey, have invented and produced a new and original Design for Badges, of which the following is a full, clear, and exact description, reference being had to the accompanying drawing, and letters of reference marked thereon, which form part of this specification.

In the drawing the figure presented illustrates a front view of the badge embodying the leading features of my novel design.

The invention consists of the new and original design embodying therein a badge ribbon, having an ornamental hanger at the one end, a medallion having a bead-like ring-shaped frame or edge connected therewith, and having a head-piece at the top of the ribbon, having a marginal configuration, as will be hereinafter more fully described and claimed.

Referring to the drawing, *a* is the ribbon portion of the badge, having the straight edges or sides *a'*. Connected with the lower edge of said ribbon *a* is an ornamental hanger *b*, having the curved portions *b'* and scallops *b''*, and depending from the portion *b''* having

such scallops *b''*, is a medallion *c*, of the shape of a circle in outline. Arranged around said medallion, in raised ornamentation, is a bead-like ring *c'*, forming a frame for the medallion. At the top of the ribbon is a head-piece or bar *d*, having the marginal configuration shown. The two longest sides of said head-piece or bar are outwardly arched, as at *d'* and *d''*, and from each arched portion *d''*, extend the outwardly and inwardly curved parts *d''*, while the shorter and end edges of the head-piece or bar are curved inwardly, as at *d''*. The hanger *b* is ornamented as at *b'*, and the whole design forms a pleasing and unique souvenir.

The ribbon *a*, as well as the medallion *c*, and the head piece *d*, may be provided with any suitable inscription or emblem.

What I claim is—

The design for a badge, as herein shown and described.

In testimony that I claim the invention set forth above I have hereunto set my hand this 6th day of June, 1894.

BENJAMIN S. WHITEHEAD.
